(74) Attorney, Agent, or Firm—Burns, Doane, Swecker & Mathis, LLP

(73) Assignee: **Philip Morris USA, Inc.**, New York, NY (US)

(57) **CLAIM**

The ornamental design for a “belt clip accessory for electrically heated cigarette smoking system”, as shown and described.

DESCRIPTION

FIG. 1 is a front perspective view of a belt clip accessory for electrically heated cigarette smoking system showing our new design;

FIG. 2 is a rear perspective view thereof.

FIG. 3 is a right side elevational view thereof.

FIG. 4 is a front elevational view thereof.

FIG. 5 is a left side elevational view thereof.

FIG. 6 is a rear elevational view thereof.

FIG. 7 is a bottom view thereof; and,

FIG. 8 is a top view thereof.
